(57) **CLAIM**

The ornamental design for a tile as shown and described.

DESCRIPTION

FIG. 1 illustrates a top perspective view of a tile in accordance with certain embodiments;

FIG. 2 illustrates a bottom perspective view of the tile of FIG. 1;

FIG. 3 illustrates a top view of the tile of FIG. 1;

FIG. 4 illustrates a bottom view of the tile of FIG. 1;

FIG. 5 illustrates a first side view of the tile of FIG. 1;

FIG. 6 illustrates a second side view of the tile of FIG. 1;

FIG. 7 illustrates a third side view of the tile of FIG. 1;

FIG. 8 illustrates a fourth side view of the tile of FIG. 1;

FIG. 9 illustrates a magnified top view of the detail of the top surface of the tile of FIG. 3; and,

FIG. 10 illustrates a magnified side view of the detail of the top surface of the tile of FIG. 8.

The dash-dash broken lines in the figures depict portions of the tile that form no part of the claimed design. The dot-dash and dot-dot-dash broken lines represent boundaries of the enlarged views and form no part thereof.

The surface shading of FIGS. 1 and 3 denotes the texture as shown in the enlarged view of FIG. 9.
